US0D1092670S

(12) **United States Design Patent** (10) Patent No.: **US D1,092,670 S**
(45) Date of Patent: ** Sep. 9, 2025

(54) **HANDGUARD**

(71) Applicant: **WHG PROPERTIES, LLC**, North Wales, PA (US)

(72) Inventors: **William H. Geissele**, Lower Gwynedd, PA (US); **Frank E. Robinson**, Schwenksville, PA (US)

(73) Assignee: **WHG PROPERTIES, LLC**, North Wales, PA (US)

(**) Term: **15 Years**

(21) Appl. No.: **29/872,864**

(22) Filed: **Mar. 21, 2023**

(51) **LOC (15) Cl.** 22-01

(52) **U.S. Cl.**

USPC **D22/108**

(58) **Field of Classification Search**

USPC D22/100, 101, 103, 104, 105, 108, 109, D22/199

CPC F41C 3/00; F41C 7/00; F41C 23/16; F41A 21/32; F41A 21/34; F41A 21/38; F41A 21/36; F41G 11/003

(57)

CLAIM

The ornamental design for a handguard as shown and described.

DESCRIPTION

FIG. 1 is a perspective view of a handguard showing the new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The broken lines illustrate features of the handguard that form no part of the claimed design.

1 Claim, 4 Drawing Sheets
